UNITED STATES PATENT OFFICE

2,441,503

SAFETY TYPE VERTICAL DOOR MOUNTING
AND OPERATING CONTROLRoy W. New, Covington, Ky., assignor to The Kirk
& Blum Manufacturing Company, Cincinnati,
Ohio, a corporation of Ohio

Application May 10, 1943, Serial No. 486,465

4 Claims. (Cl. 110—176)

1

The present invention relates to industrial oven doors of the vertically-operating type, and has for an object the provision of a safety-type of vertical door mounting and operating control.

Another object of the invention is to provide for safe and easy operation of large and heavy oven doors of this type with a minimum of power consumption.

A further object of the invention is to provide a door mounting and control whereby the door is snugly sealed when in fully closed position and, at all other times, is movable freely without danger of damage to the heat seal about the door opening in the oven.

Still another object of the invention is to provide an arrangement whereby danger to persons and property is eliminated in the event of failure of the counterweight mechanism.

These and other objects are attained by the means herein described and disclosed in the accompanying drawings, in which:

Fig. 1 is a front end elevational view of an industrial oven embodying the door control of the invention, parts being broken away, and parts being shown in cross-section.

Fig. 2 is an enlarged fragmental view of the structure in the left center of Fig. 1.

Fig. 3 is a cross-sectional view taken on line 3—3 of Fig. 2.

Fig. 4 is a cross-sectional view taken on line 4—4 of Fig. 1.

Fig. 5 is a cross-sectional view taken on line 5—5 of Fig. 4.

Fig. 6 is a cross-sectional view taken on line 6—6 of Fig. 4.

The utilization of vertically opening doors on one or both ends of industrial ovens has become increasingly common in the various fields of production due to the numerous advantages in saving of floor space in the plant and reducing congestion in moving materials by trucks into and around the ovens. The large and heavy doors of this type have presented a hazard to the safety of persons, material and equipment in the past, due to the fact that they were suspended by cables or chains extending over pulleys and having counterweights. Breakage of the counterweight mechanism always endangered persons and equipment beneath, and even partial breakage frequently imposed dangerous strains or ac-

tual damage to the oven structure itself unless the latter were constructed more sturdily than otherwise required by the normal duty of the industrial oven.

By the present invention all of these hazards are obviated.

With reference to the drawings, it is to be noted that industrial ovens of the class herein illustrated are frequently provided with a door at each end, and that since the doors and their mounting and control mechanisms are substantial duplicates, only one end of the oven need be described for a full and complete understanding of the invention.

In Fig. 1, the oven is indicated generally at 10, and is preferably constructed of metal-clad insulating sidewalls 14 and metal-clad insulating roofing panels 12 arranged to form a tunnel-shaped body of desired length, height and width to accommodate the passage of trucks or conveyors for carrying materials to be subjected to drying, baking or the like.

At each end of the oven a door opening 13 is provided where the inturned end portions 14 of sidewalls 14 are suitably joined to uprights 15 on either side of each opening 13. Each of the uprights 15 is made up of a front guide plate 16 and a rear guide plate 17 secured by bolts or by welding (not shown) to the flanges of a vertical channel member 18 which also has the end reinforcement channel member 19 of wall portion 14 secured to it. The sturdy uprights 15 extend upwardly substantially twice the height of the oven and the portions above the oven roof 12 may have other structural members (not shown) secured to them in known manner to support heating and air circulating equipment (not shown) for the oven in the space above the roof 12 in order to save floor space.

Secured to the outer faces of said front guide plates 16 and to the outer faces of the rear guide plates 17 are cross channels 20 and 21, respectively, which connect the upright 15 on either side of the doorway and also form a mounting for the door operating mechanism hereinafter described. Mounted on the inner opposed faces of guide plates 16 and 17 are guide angles 22 and 23, respectively. On a common side of these guide angles are secured guide strips 24 and 25, respectively. As can be best seen in Fig. 4, the

2

guide angle 22 on the front guide plate 16 extends almost the full length of said plate. A short distance from the lower end of the plate, the guide angle 22 has a widened portion affording an offsetting of the free edge of said guide angle at 26 and a short arcuate shoulder 27 at the junction of the offset. The guide angle 23 is arcuately cut away on its free edge at 28 slightly above the level of the opposed shoulder 27. The shoulders 27 and 28 together form an abrupt curve, toward the inside face of rear guide plate 17, in a wheel guide slot bounded by the salient edges of guide angles 22 and 23. On this inside face of guide plate 17 is a heat seal strip 29.

In a similar fashion, guide strips 24 and 25 form a wider and shorter guide wheel slot which terminates at its lower end a short distance below the level of the top of door opening 13. The guide strip 24 has a shoulder 30 corresponding to shoulder 27 on guide angle 22 and the guide strip 25 is shouldered or cut off at 31 corresponding to shoulder 28 on guide angle 23.

Mounted on opposite vertical edges of the vertical oven door 32 near the top are freely rotatable guide wheels 33 which travel in the guide slot defined by guide strips 24 and 25. Near the bottoms of the vertical edges of door 32 are smaller guide wheels 34 each having an enlarged spacer or flange 35 to assure that said wheels 34 shall follow in the guide slots between guide angles 22 and 23.

It will be noted, from an inspection of Fig. 4, that when guide wheels 33 and 34 engage shoulders 30 and 27 respectively during downward movement of the door, said door will be shifted bodily from a vertical plane wherein the inside face of the door clears the heat seal strips 29 to a position of firm abutment against said seal strips without any appreciable scraping of said door on said strips.

The location of said shoulders with relation to the oven floor 35 and of the guide wheels with relation to the bottom of the door is such that the door automatically seals the opening at the approximate instant it touches the floor, and breaks said seal, without scraping over the heat seal strips as soon as the bottom of the door leaves the floor.

It should be noted that the edge of the roof 12, above the door opening 13, terminates in the plane of the rear faces of guide plates 17 (see Fig. 3), and that a depending insulating flange 36 which defines the top of door opening 13 has a heat seal strip 37 thereon, the face of which lies in a common plane with the faces of heat seal strips 29.

The weight of the door 32 is counterbalanced by means of a pair of cables 38 which pass over pulleys 39, through holes 40 in channel members 18 of the uprights, and over pulleys 41 on the brackets 420 at the tops of uprights 15. Cables 38 are suitably attached to rings 42 in the tops of blocks 43 from which the door is suspended. Counterweights 44 on the ends of the cables operate within vertical casings 45 at opposite sides of the oven.

The door and its mounting as thus far described form a sort of unitary structure which does not depend upon the strength of the body of the associated oven for its support, but on the contrary, it provides ample support for a structurally weak oven body if such be desired. The door 32 is nicely counterbalanced and is therefore adapted to be raised or lowered with very

little power by the following described operating and safety holding mechanism.

This mechanism is built into and supported by the uprights 15 and the cross-members which connect said uprights at their tops. The mechanism consists generally of a power driven jack screw 46 rotatably supported in each upright 15, jack nuts 47 on said screws, with links 48 connecting said nuts with the blocks 43 on the top of the door 32, the jack screws having sprockets 49 fixed thereon and connected by drive chains 50 and 51, respectively, which are carried by sprockets 52 on a reversible vertical motor 53.

The lower end of each jack screw 46 is journaled in a bottom flanged end bearing 54 which is secured to an angle bracket 55 secured to the face of the channel member 18 of the upright 15. (See Fig. 2.) The upper end of each jack screw 46 is journaled in a bearing 56 secured to a plate 57 which is secured to the top end edges of guide plates 16 and 17, as by welding, and which plate has a bore through which the jack screw extends into its bearing.

Immediately under the respective drive chains 25 are vertically adjustable chain guide sheets 58 and 59, adjacent the edges of which are upright guard sheets 60 and 61 which span the space between the uprights to give the entire structure a finished appearance and prevent chains 50 and 51 from being accidentally disengaged from the sprockets or from dropping to the floor in the event they become loose or broken.

By reference to Fig. 2 it will be noted that the jack nut 47 has an integral trunnion 62 over 35 which passes the upper perforated end of link 48, while the block 43 on the door has a trunnion 63 to receive the lower end of said link. It will be readily understood that this linkage suspension of the door 32 in cooperation with the upper and lower guide wheels 33 and 34 riding between their angle guides and guide strips respectively, will insure free and easy raising and lowering movement whenever the motor 53 is operated in the proper direction. The normal slow pitch of the 40 threads on the jack screw and its nut will positively arrest and hold the door at any elevation when the motor is at rest. Even in the event of 45 breakage of one or both of the counterweight cables 38 the door is precluded from falling by the linkage and jack nut suspension.

The action of the door guide wheels at the shouldered portions of the guide slots is such that the door retains its vertical position and also shifts bodily to and from a tightly sealed relation 55 with the oven doorway as the door reaches or leaves a fully lowered position in its vertical movement. This action is completely automatic and permits of the use of materials in the heat sealing strips that are most effective but which 60 would not hold up under a sliding contact with the door.

The wiring and control switch stations (not shown) for the reversible motor 53 may be disposed according to approved practices and convenience.

The operation of the device and its efficiency and complete safety will be fully understood from the foregoing description.

For normal raising and lowering of the door 70 the current consumption of motor is very low because the great weight of the large door 32 is fully counterbalanced by the weights 44, and the motive power required is but little more than enough to drive the jack screws and overcome a small amount of inertia in the masses and fric-

tion in the moving parts. If desired the motor may be selected to raise and lower the door only when the counterweights and cables are also effective to sustain the weight of the door and in that way preclude the operation in the event of failure either of the cables 38.

When the door is fully closed it is held snugly against the heat seal strips due to its weight and the action of its guide wheels on the shoulders of the guide strips and guide angles and more particularly because the threaded engagement of the jack screws in the jack nuts constitutes an irreversible connection. This tight seal protects persons not only against the discomfort of heat leakage around the door, but when the oven is used for baking enamels or lacquers on articles in the oven the danger to persons near the door is eliminated in the event of an explosion.

The door mounting and control of the invention will in practice render unnecessary the compulsory inspections currently required in the industries for vertical doors, because there is no danger of a falling door even though the counterweight mechanism fails. Furthermore, the guided condition of the door precludes injury to the hand of the worker if the hand should be inserted between the door and the front guide plate of the upright.

There is thus attained a very high degree of safety from all of the hazards that normally attend the use of industrial ovens and at the same time the control of the door is simple and entirely automatic.

What is claimed is:

1. In a vertical door mounting and operating mechanism for an industrial oven the combination of a pair of vertical uprights defining the sides of an oven door opening and extending above such opening, means on said uprights forming guide slots, a vertical door extending between the uprights, guide members on the door and engaging the guide forming means and operating in the guide slots for normally retaining the door in slightly spaced relation to the uprights when the door is at least partially raised, shoulders on the guide slot forming means downwardly inclined toward the door opening and spaced from the bottoms of the uprights at distances corresponding to the spacing of the respective guide means on the door from the bottom of the door whereby the door is moved into and from sealing abutment with the uprights as the door moves into and from a fully lowered position, power driven jack screws mounted in the uprights, cooperating jack nuts on said screws, links pivotally connected at opposite ends to the sides of the jack nuts and the top of the door with their pivotal axes disposed horizontally in a plane parallel with the major faces of the door for raising and lowering said door and pulley-supported cable and counterweight means normally sustaining the weight of the door.

2. In a vertical oven door mounting and operating structure the combination with a vertical oven door, of a pair of vertical uprights disposed one at each side of the door, each upright comprising a front guide plate and a rear guide plate between which plates a vertical edge margin of the door may freely operate, vertical guide angles disposed in opposed relation on adjacent faces of said guide plates of each upright to form a guide slot between them and provided with offset shoulders downwardly inclined toward said rear guide plate at a predetermined elevation from the base of the upright, guide strips secured along-

side the respective guide angles to form between them another guide slot and provided with offset shoulders inclined downwardly toward said rear guide plate at a different elevation from the base of the upright, a pair of guide wheels on each side of the door and arranged for operation one each in the respective guide slots in peripherally tracking engagement with the edges of said guide angles and said guide strips respectively, said

wheels being vertically spaced apart from each other at a distance substantially equal to the distance between the first-mentioned offset shoulders and the second-mentioned offset shoulders, and means for raising and lowering the door comprising power driven jack screws mounted in the respective uprights, jack nuts on said jack screws and links pivotally connected at their opposite ends to the sides of said jack nuts and the top of the door, the pivotal axes of said links being disposed horizontally in a plane parallel to the major faces of the door.

3. In an industrial oven the combination of insulating sidewalls having a doorway opening therein, a pair of uprights disposed respectively at opposite sides of said opening, a vertically movable door extending between the uprights and overlapping the opposite sides of the doorway opening, counterweight means for suspending the door in vertically adjusted positions, irreversible power driven means comprising vertical jack screws supported by the uprights and jack nuts thereon, means including pivoted links forming a flexible connection between said nuts and the top of the door and having their pivotal axes disposed horizontally in a plane parallel with the major faces of the door for raising and lowering said door, cooperating guide means on said uprights and the side edges of the door adjacent thereto for holding the door in non-contacting relation to the uprights when the door is disposed at any elevation above a fully lowered position, one of said guide means including inclined shoulders arranged and adapted for contact with the other of said guide means when the door is disposed closely adjacent a fully lowered position for bodily shifting said door to and from contact with the uprights as said door is moved into and from fully lowered position opposite the door opening.

4. In an industrial oven the combination of a sidewall provided with a door opening, a pair of opposed, channel shaped uprights at the vertical sides of the door opening, a vertical door having its side edges extending into the opposed openings of the channel shaped uprights, guide wheels rotatably mounted adjacent the top and bottom of each side edge of said door and disposed in offset planes parallel to said edges of said door, parallel strips secured in opposed relation on opposed inner faces of said channel shaped uprights forming guide slots and tracking edges for diametrically opposite sides of each of said guide wheels, the strips engaged by the upper guide wheels being sloped in the direction of the door opening at a distance above the bases of the uprights corresponding approximately to the location of said upper guide wheels from the bottom of the door, the strips engaged by the lower guide wheels being inclined toward the door opening at a distance from the bases of the uprights corresponding to the approximate distance of the lower guide wheels from the bottom of the door, the inclined portions on all of said guide strips engageable by the respective guide wheels on the door for shifting the door bodily to and from

abutment with the uprights at the sides of the door opening, as said door is moved vertically to and from fully lowered position, and means for raising and lowering the door including synchronously driven jack screws supported on the uprights, jack nuts travelable thereon, and links connected at opposite ends with said nuts and the top of the door with the pivotal axes thereof disposed horizontally in a plane parallel with the major faces of the door.
